UNITED STATES PATENT OFFICE.

JAMES L. HICKS, OF DONIPHAN, MISSOURI.

SWING.

1,260,671.

Specification of Letters Patent. Patented Mar. 26, 1918.

Application filed June 21, 1916. Serial No. 104,976.

To all whom it may concern:

Be it known that I, JAMES L. HICKS, a citizen of the United States, and a resident of Doniphan, in the county of Ripley and State of Missouri, have invented a certain new and useful Improvement in Swings, of which the following is a specification.

My present invention relates to swings, and more particularly to swings of that nature which are suspended by means of flexible connections, such as chains, from an overhead support, my object being to provide a swing of this nature, the motion of which may be readily and quickly controlled by the occupant thereof, and the structure of which will be simple, inexpensive, and durable.

To this end I preferably provide a swing, such as shown in the accompanying drawing, forming a part of this specification, and wherein—

Figure 1 is a perspective view illustrating the practical application of my invention.

Fig. 2 is an end elevation of the swing, and

Fig. 3 is a detail section taken substantially on line 3—3 of Fig. 2.

Referring now to these figures, it will be noted that I provide in the first instance, a rigid, rectangular seat frame 10, the end bars 11 of which are extended at their ends materially beyond the side bars 12.

I likewise provide a rigid back frame 13, the end uprights 14 of which may have forwardly projecting arm rests 15 braced, for instance, by diagonal braces 16, and are extended at their lower ends and pivotally connected at 17 to the rear projecting ends of the end bars 11 of the seat frame, permitting the back frame 13 to flex with respect to the seat frame 10 in the swinging movements of the structure.

A foot rest 18 in the form of a cross strip, is secured to the lower ends of uprights 19, which latter are pivotally connected as at 20 at points intermediate their ends, to the forward extensions of the end bars 11 of the

seat frame 10, the upper extremities of the uprights 19 extending approximately the height of the arm rests 15.

The end uprights 14 of the back frame 50 and the upper ends of the uprights 19 of the foot rest, are similarly provided with eyes, staples, or the like, as indicated at 21, to receive the lower ends of the flexible suspension members, such, for instance, as chains 55 22, as seen in Figs. 1 and 2, which it will be noted are separate from one another.

As thus constructed, and separately suspended at four points, the swing as proposed by my invention, including as it does but four pivotal connections, is well designed to carry out the foregoing objects with respect to simplicity, economy, and durability, and also provides for the ready and easy control of the swinging movement thereof, by the operator, through the foot rest and its uprights fulcrumed upon the seat frame, and acting in the control of the swinging movements, as levers.

I claim:

70
A suspended swing including a substantially horizontal rectangular seat frame, an upright rectangular back frame pivoted at its lower portion to the rear portion of said seat frame and extending in whole above the 75 seat frame, a footrest parallel to and below the seat frame having end uprights intermediate pivoted to the forward side portions of the seat frame and otherwise unconnected to either the seat frame or back frame and 80 movable independently thereof, portions of said uprights of the foot rest extending above the seat frame, and separate suspension members independently connected to the upper side portions of the back frame 85 and the upper extremities of said upwardly projecting portions of said uprights, all for the purpose described.

JAMES L. HICKS.
